UNITED STATES PATENT OFFICE

WILLIAM F. KIESEL, JR., OF HOLLIDAYSBURG, PENNSYLVANIA

SMOKE BOX FRONT

Application filed July 6, 1931. Serial No. 548,963.

This invention relates to smoke box fronts for locomotives or the like, and more particularly to the combination of a smoke box front of novel design with a shrouded stack.

5 The primary object of the invention is to provide a locomotive smoke box and stack arrangement of a design such that, when the locomotive is moving, air will be entrained at the front of the locomotive and deflected upwardly around the rear of the stack to lift the smoke and gases issuing therefrom well above the locomotive cab, thus clearing the atmosphere at the front of the locomotive and giving the engine crew a clear view ahead.

10 While I am aware that it has heretofore been proposed to provide a locomotive stack with a hood partly surrounding it for the purpose of deflecting a current of air upwardly at the rear of the stack to carry smoke and gases above the line of vision of the 15 engine crew, the present invention is characterized by a number of improvements over such schemes among which improvements the following may be mentioned.

20 In the present invention the smoke box front is inclined upwardly and rearwardly and so formed and related to the stack as to entrain and concentrate a relatively large volume of air around the rear of the stack.

25 The stack and smoke box front comprise an integral casting so that, when the smoke box front is removed, the stack and the shroud associated with it are removed by the same 30 operation, which immediately renders the internal piping and other parts within the smoke box readily accessible. Furthermore, the smoke box front is preferably also provided with a forwardly projecting portion normally covered by a door through which

35 access may be had to the smoke box without removal of the combined smoke box front and stack.

40 Other objects and advantages characteristic of this invention will become more fully apparent from the description of one embodiment or example thereof which follows hereinafter, having reference to the accompanying drawings, whereof:

45 Fig. I represents a front elevation of the forepart of a locomotive with certain parts

shown in section and others removed for clearness of illustration.

Fig. II represents a top plan view of the same; and,

55 Fig. III represents a longitudinal cross section of the same, taken as indicated by the lines III—III of Fig. II.

In the drawings the front end of the boiler barrel of a locomotive is designated at 1, and portions of tubes through which the products of combustion pass to the smoke box are designated at 2. At the top of the tube sheet 3 there is also shown the usual dry pipe 4 and T connection 5, but the details of the superheater, superheater header, and other 60 parts normally found within the smoke box have been omitted for the sake of clearness of illustration, inasmuch as the present invention is not concerned with the interior fittings of the smoke box. In advance of the boiler barrel 1 and at the top of the smoke box, there is a front end casting 6 with a feed water heater 7 thereon.

65 The cylinder and saddle construction need not be here described in detail as the preferred arrangement thereof is that which is disclosed in U. S. Letters Patent No. 1,785,485, granted to me December 16, 1930. The main piston-type valve chambers are shown at 8 and the auxiliary or cut-off valve 75 chambers are shown at 9. Exhaust steam passages 10 lead upwardly around the auxiliary valve chambers 9 to flanges 11 where these passages connect with pipes 12 which conduct the exhaust steam to the feed water 80 heater. Additional transverse passages 13

85 chambers are shown at 14. From the ends of the valve chambers 8 to a vertical conduit 14 and from thence to the exhaust stand 15 directly thereabove. At the bottom of the smoke box 90 there is a plate 16 having an annular depression 17 concentric with and surrounding the exhaust stand 15. This bottom plate 16 is preferably formed integrally with the valve chambers 8 and 9 and the exhaust steam conduits 10, 13 and 14, and the complete casting

95 comprises a saddle for the forward end of the boiler barrel 1. At its rear end the smoke box bottom plate 16 is joined to the boiler barrel 1 as shown at 18.

The details of the means provided for imparting the required velocity to the exhaust gases passing from the smoke box to the atmosphere are shown and described in U. S. Letters Patent No. 1,749,487, granted to me March 4, 1930, and, therefore, need not be here referred to other than briefly. The central raised portion 19 of the smoke box bottom plate 16 forms, together with the circular base 20 of the exhaust stand 15, a seat for a cylindrical netting 21. The top of the netting 21 is disposed within a blower ring casting 22 of a well-known construction.

The top flange 23 of the ring casting 22 abuts against a corresponding flange 24 formed at the base of the inner portion 25 of the stack 26. Connected to the depending flared skirt 27 of the ring casting 22, there is a petticoat 28 preferably constructed in the manner described in my Patent No. 1,749,487, referred to above. The petticoat 28 may be made in three sections, each extending through an arc of 120°, with two sections bolted to the blower ring 22 and with the third or front section hinged to the bottom of the other two and latched to the blower ring 22 by a dog 29, so that it may be swung forward to permit access to the netting 21 for the purpose of inspection. The dog 29 is pivoted to a bracket 30 and has a lug 31 which is adapted to be clamped against the inside of the ring casting 22. To hold the handle portion 32 of the dog 29 in clamped position, a bolt 33 with a cotter pin 34 at the end thereof may conveniently be employed. When the locomotive is not in motion and no steam is exhausting from the cylinders, by opening a valve in the cab, live steam may be admitted to the blower ring 22 and caused to issue from apertures therein in a jet, as indicated in Fig. III, to induce a draft in the stack 26 and thus to lift the smoke.

From the description thus far it will be apparent that flue gases from the tubes 2 pass through the smoke box to the bottom thereof at the space between the annular depression 17 of the smoke box bottom plate 16 and the bottom of the petticoat 28. From thence the flue gases pass upward through the cylindrical netting 21, where large cinders are broken up into particles suitable for passage through the netting. A draft inducing jet of steam is projected upward from a suitable exhaust nozzle attached to the exhaust stand 15 at 35, and causes the flue gases to be entrained therein and to be ejected upwards through the stack 26 with considerable velocity.

The above described smoke box construction, the arrangement of the exhaust steam conduits, and the means provided for inducing a draft in the flue gases within the stack 26 represent merely an example of the interior construction of a locomotive front end to which my invention may be applied; and

it is to be understood that the invention is not limited in its application to such a construction as that described and illustrated herein, but may be applied to many different types of locomotive front ends.

To the portion 36 of the saddle and to the front end casting 6, cylindrical plates 37, defining the side walls of the smoke box, are riveted. As shown in Fig. I, there is a ring 38 of substantially square cross-section fitting within the front end of the smoke box and slanting upwardly and rearwardly, the smoke box ring 38 being attached to the margins near the front edges of the bottom plate 16, the cylindrical plates 37, and the front end casting 6. The ring 38 serves as a support upon which the smoke box front, comprehensively designated at 39, is mounted.

The smoke box front 39 includes a flat slanting wall 40 which is of substantially circular outline and which is bolted at its peripheral margin 41 to the smoke box ring 38. The exterior portion 42 of the stack 26 projects upwardly at the outside of the wall 40 to a point somewhat above the feed water heater 7, and the interior portion 25 of the stack projects downwardly at the inside of the wall 40 to the ring casting 22. The entire stack 26 is formed as an integral part of the smoke box front. At the front of the stack there is an opening 43. Adjacent to this opening the wall of the stack is formed to take the shape of a nozzle 44 having its axis inclined to the vertical axis of the stack 26. At the sides of the nozzle 44 there are brackets 45 which may serve as supports for a headlight and generator. The steam exhaust from the headlight generating apparatus may be connected to the nozzle 44 to inject steam from the exhaust into the stack 26.

Formed integrally with the flat slanting wall 40 at the top portion thereof there is a shroud 46, the top edge of which, as shown in Fig. II, is circular and surrounds the major portion of the stack. At the front of the stack 26, the shroud 46 merges into forwardly projecting wings 47 which extend upward from the bottom of the slanting wall 40 of the smoke box, and converge towards the top of the stack. The wings 47 project to a considerable distance in advance of the wall 40 and form with it a trough which serves to deflect air, especially when the locomotive is running at high speed, upwardly and rearwardly along the slanting wall 40 to the space between the stack 26 and the shroud 46, where the air is directed vertically upward in a current surrounding the smoke and gases issuing from the stack. Exhaust steam from the headlight generator may be injected into the stack at the nozzle 44.

There is also formed integrally with the smoke box front a cylindrical forwardly projecting portion 48 which serves as a manhole through which access may be had to the inte-

rior of the smoke box without removal of the smoke box front. The cylindrical portion 48 is provided with a flange 49 to which a smoke box door is normally hinged and bolted. Perforated lugs 50 are provided at the front of the cylindrical portion 48, these lugs serving as hinge supports for the smoke box door which is not shown in the drawings but may be assumed to be of a shape corresponding to the flange 49.

It will be particularly noted that the smoke box front comprises in an integral piece the slanting wall 40, the stack 26, the shroud 46, the forwardly projecting wings 47, and the cylindrical portion 48. Accordingly, all of these parts are adapted to be removed in a single operation which involves merely the removal of the nuts on the bolts by which the slanting wall 40 is secured to the ring 38 at the front end of the locomotive. When the smoke box front has been removed, the interior piping is at once accessible. Furthermore, it is possible to enter the smoke box without removal of the smoke box front through the manhole defined by the cylindrical portion 48.

When a locomotive provided with a front end and smoke box front constructed according to the practice of this invention is standing idle, the draft induced in the stack by steam from the blower ring 22 is sufficient to lift the smoke and flue gases well above the top of the stack; and there is no interference with the vision of the engine crew. When the locomotive is moving the air impinges on the slanting wall 40 of the smoke box front, and is deflected upwardly and rearwardly in the trough formed between the wings 47 and the slanting wall 40. Accordingly, the stream of air is directed into the annular space between the shroud 46 and the stack 26 and from thence is deflected vertically upwards in a column surrounding the flue gas issuing from the stack. This raises or lifts the smoke and gases from the stack well above the top of the locomotive so that the view of the engine crew is not interfered with.

While I have described my invention with reference to one example or embodiment thereof, it will be apparent that various changes may be made in the form of the structure herein disclosed without departing from the spirit of my invention as defined in the claims hereto annexed, and that some of the characteristic features of my novel smoke box front may be used to advantage without a corresponding use of other features.

Having thus described my invention, I claim:

63 1. A removable smoke box front for a locomotive or the like comprising in an integral piece, a slanting wall, a stack, and air-deflecting means for producing an upward current of air at said stack.

63 2. A removable smoke box front for a loco-

motive or the like comprising in an integral piece, a slanting wall, and a stack having a portion projecting upwardly at the outside of said wall, and a portion projecting downwardly at the inside of said wall. 70

3. A removable smoke box front for a locomotive or the like comprising in an integral piece, a slanting wall, a stack, and forwardly projecting wings for producing an upward current of air at said stack. 75

4. A smoke box front for a locomotive or the like comprising in an integral piece, a slanting wall, a stack, and a shroud surrounding the rear of said stack but open at the front of the stack and merging into forwardly projecting wings for producing an upward current of air at said stack. 80

5. A smoke box front for a locomotive or the like comprising in an integral piece, a flat slanting wall, a stack having a portion thereof projecting upwardly at the outside of said wall and a portion thereof projecting downwardly at the inside of said wall, and a shroud surrounding the rear of said stack but open at the front of the stack and merging into forwardly projecting wings for producing an upward current of air at said stack. 85

6. In combination with a boiler barrel of a locomotive or the like, a removable smoke box front comprising an upwardly and rearwardly slanting wall, a stack thereon, and means partly surrounding said stack and extending forwardly from said slanting wall for producing an upward current of air at said stack. 95

7. In combination with a boiler barrel of a locomotive or the like, a removable smoke box front comprising an upwardly and rearwardly slanting wall, a stack thereon, a shroud surrounding the rear of said stack, and forwardly projecting wings on said slanting wall. 100

8. In combination with a boiler barrel of a locomotive or the like, a smoke box front comprising an upwardly and rearwardly slanting wall, a stack thereon, and a shroud surrounding the rear of said stack but open at the front thereof, and forwardly projecting wings on said slanting wall, said wings converging towards said shroud and merging therewith. 110

9. In combination with a boiler barrel of a locomotive or the like, a smoke box front comprising an upwardly and rearwardly slanting wall, a stack passing through said wall and formed integrally therewith, a shroud surrounding the rear of said stack, and forwardly projecting wings on said slanting wall converging towards said shroud and merging therewith, said wings extending upward to the top of the stack. 120

10. In combination with a boiler barrel of a locomotive or the like, a removable smoke box front comprising an upwardly and rearwardly slanting wall, a stack thereon, and means partly surrounding said stack and ex- 130

tending forwardly from said slanting wall for producing an upward current of air at said stack, said smoke box front having a covered opening beneath said stack permitting partial access to the smoke box.

11. A removable smoke box front for a locomotive or the like comprising in an integral piece, a slanting wall, a stack, air-deflecting means for producing an upward current of air at said stack, and a cylindrical projection extending forward from said wall beneath said stack, said projection defining a manhole permitting partial access to the locomotive smoke box and boiler front.

15. In testimony whereof, I have hereunto signed my name at Altoona, Pennsylvania, this 25th day of June 1931.
